THOMAS KERR, OF LONG ISLAND CITY, NEW YORK, ASSIGNOR TO CROMPTON & KNOWLES LOOM WORKS, OF WORCESTER, MASSACHUSETTS, A CORPORATION OF MASSACHUSETTS

ELECTRICAL WEFT DETECTOR FOR LOOMS

Application filed April 6, 1931. Serial No. 527,981.

This invention relates to improvements in weft detectors for looms and it is the general object of the invention to provide a detector of this type which shall depend upon presence of the shuttle in the shuttle box to complete an electric circuit and cause said detector to function.

The usual loom operates with shuttle boxes of which one side is usually defined by a movable shuttle engaging binder. This binder is ordinarily held in a shuttle checking position by a spring and is thrown out by the shuttle as the latter enters the box. The outward movement not only checks the shuttle but also depresses the protection dagger so that the loom may continue to operate. It is an important object of my present invention to close the loom controlling circuit by the outward or shuttle checking movement of the binder.

It is another object of my invention to provide a detector of the caliper type which is lowered into the top of the shuttle by a cam controlled spring during the forward movement of the lay, the arrangement being such that as the lay starts on its backward movement the detector will be raised from the shuttle box prior to the picking of the shuttle.

With these and other objects in view which will appear as the description proceeds, my invention resides in the combination and arrangement of parts hereinafter described and set forth in the claims.

In the accompanying drawing wherein a convenient embodiment of my invention is set forth,

Fig. 1 is a top plan view of a portion of a loom having my invention applied thereto,

Fig. 2 is a vertical section on an enlarged scale taken on line 2—2 of Fig. 1,

Fig. 3 is a detail plan view similar to a portion of Fig. 1 but showing the binder in circuit breaking position, and

Fig. 4 is a detailed top plan view in the direction of arrow 4, Fig. 2.

Referring to the drawing, I have shown a loom frame 10 and a lay 11 on which is mounted a box front 12 secured to the lay in any approved manner and defining the front wall of the shuttle box 13. The box

back 14 is provided with a slot 15 in which moves horizontally the binder 16. The latter may be made of wood if desired and is pivoted as at 17 to the lay. A binder spring 18 secured to the lay pushes the binder normally forwardly to hold the same in the position shown in Fig. 3. The shuttle S may be provided with a bobbin B having a supply of weft W which is depleted as weaving continues.

The box back 14 has upstanding therefrom a bracket 20 having a bearing 21 through which extends a spring plunger or rod 22. The latter has a detecting head 23 which is adapted for engagement with the weft at a point below the bearing 21. A compression spring 24 surrounds the upper part of the rod 22 and exerts a downward pressure on the collar 25 adjustably secured to the rod. A stop 26 carried by the bracket 20 receives the upward thrust of the compression spring. The bracket may be held to the box back by means of screws 27 and will be rigid with the lay so as to move back and forth with the latter.

A stand 30 may be bolted to the loom frame and has a tongue 31 and shoulders 32 which receive the right hand ends of actuating cam plates 33 as viewed in Fig. 2. Each of said plates has the forward or left hand end thereof as viewed in Fig. 2 formed with a downwardly and forwardly extending cam surface 34. The upper end of the plunger or rod 22 is provided with a cross head 35 which is positioned to rise over the cams 34 of the plates 33.

In operation, when the lay is in its rearward position the cross head 35 will be on the horizontal dwell portion 36 thereof so that the head 23 will be held above the path of the shuttle, the spring 24 being compressed. As the lay moves forwardly the cross head will move downwardly along the inclines 34 under action of spring 24 until the head on the lower end of the rod 22 engages the weft. So long as a working supply of weft is present the collar 25 will be out of engagement with a contact plate 37 supported by but insulated from the bearing 21 by means of a plate of insulating material 38.

Said contact 37 has an opening 39 larger than the rod 22 so as to be out of contact with the latter at all times and may be held in position by means of a screw 40 passing 5 through an insulating bushing 41.

When insufficient weft for continued weaving remains on the bobbin B the head 23 will be permitted to descend far enough to effect contact between the collar 25 and the contact 10 plate 37. When this contact is established current will rise from the ground, pass through wire 42, collar 25, contact 37, wire 43 to a contact 44 secured to box back. Under these conditions the binder will be in the position shown in Fig. 1 and current may 15 therefore flow through a spring clip 45 secured to the binder and connected by wire 46 as shown in Fig. 2 to a source of electric power P, wire 47 extending to an electro- 20 magnetic device M which is connected by wire 48 to the ground. Current flowing in this circuit will energize the device M which for the purpose of the present invention may 25 represent any one of several known devices for producing a change in the operation of the loom. Such a change may be the replenishment of weft in a running shuttle, an exchange of shuttles, or loom stoppage.

As the lay recedes the cross head will be 30 moved forwardly to assume the dotted line position shown in Fig. 2, thus withdrawing the detector head 23 from the path of the shuttle. This latter action takes place prior 35 to picking.

From the foregoing it will be seen that I 40 have provided an electrical weft detector employing an electric circuit which is dependent for its closure upon the binder. It will also be seen that the detector rod is controlled so that it can be in the shuttle a sufficient length of time to detect the weft but will be at all times out of the path of the shuttle when the latter is in motion along 45 the lay.

Having thus described my invention it will be seen that changes and modifications may be made therein by those skilled in the art without departing from the spirit and scope of the invention and I do not wish to be limited to the details herein disclosed, but what I claim is:

1. In a loom having a lay and a shuttle, a 55 binder on the lay to be engaged and moved by the shuttle, an electric binder contact to be closed by the binder, electrically actuated means to change the operation of the loom, an electric weft detector for the shuttle, and an electric circuit to include the binder contact and the detector means, the closing of the 60 circuit being dependent upon movement of the binder by the shuttle.

2. In a loom having a lay and a shuttle, a 65 binder on the lay to be engaged and moved by the shuttle, an electric binder contact to be

closed by the binder, electrically actuated means to effect a change in the operation of the loom, an electric weft detector, and an electric circuit to include the binder contact and detector and dependent for closure upon a predetermined degree of exhaustion of the weft in the shuttle and movement of the binder to a given position by the shuttle. 70

3. In a loom having a lay and a shuttle, a 75 binder on the lay to be engaged and moved by the shuttle, electrically actuated means to effect a change in the operation of the loom, a circuit to include the means, a relatively fixed contact, and a second contact carried by and movable with the binder to engage the first 80 contact to close the circuit.

4. In a loom having a lay and a shuttle, a 85 binder on the lay to be engaged and moved by the shuttle, electrically actuated means to effect a change in the operation of the loom, a circuit to include the means, and a pair of contacts in said circuit which are caused to have electrical contact by movement of the binder under influence of the shuttle. 90

5. In an electrical weft detector for a loom having a shuttle, a lay, a detecting element mounted on and movable vertically with respect to the lay and capable of engagement with the weft in the shuttle, means to lower 95 said detecting element when the lay is in its forward position, and a pair of contacts both carried by the lay, one carried by the element and the other fixed to the lay and insulated from the element, movement of the element to a predetermined position effecting electrical engagement between the contacts. 100

In testimony whereof I have hereunto affixed my signature.

THOMAS KERR.
